UNITED STATES PATENT OFFICE.

GEORGE W. LANGFORD, OF ANN ARBOR, MICHIGAN, ASSIGNOR TO ECONOMY BALER COMPANY, OF ANN ARBOR, MICHIGAN, A CORPORATION OF MICHIGAN.

BALER.

Application filed May 17, 1919. Serial No. 297,899.

To all whom it may concern:

Be it known that I, GEORGE W. LANGFORD, a citizen of the United States of America, residing at Ann Arbor, in the county of Washtenaw and State of Michigan, have invented certain new and useful Improvements in Balers, of which the following is a specification, reference being had therein to the accompanying drawings.

10 This invention relates to balers and refers more particularly to a machine adapted for forming scrap metal, sheet trimmings, wire, etc. into bales, although the invention in certain of its broader aspects is not necessarily limited to the particular use mentioned.

Among the objects of the invention are to provide a baler which can be formed of structural iron or steel and which will have the necessary strength and rigidity while being relatively light in weight; to provide a construction in which the side frame and the compression box can be formed as a single piece if desired; to so mount the toggle mechanism and the drive mechanism that the fulcrum for the toggle is in substantially a straight line with the plunger of the compression box; to provide a construction and combination of gearing and toggle mechanism which will permit of a larger number of tons of pressure being exerted on the material than is possible with balers previously in use; to provide a construction having a relatively large compression box and in which a reducing block can be conveniently inserted for a second or final compression without opening the box; to provide an improved locking mechanism and kicker mechanism for releasing the bale; and in general to provide a baler which will rapidly and economically form metal scraps into bales and in which the mechanism is so constructed and arranged that while relatively light in weight and preferably portable, it will have sufficient rigidity and strength to stand the high pressures and stresses to which a machine of this character is subjected.

50 The invention also resides in the arrangement of the wings of the compression plunger and in such further details of construction and arrangements and combinations of

parts as will more fully hereinafter appear.

In the drawings:

Figure 1 is a side elevational view, slightly in perspective, showing a scrap metal baler embodying my invention;

Figure 2 is a perspective view looking downwardly and rearwardly on the compressor box;

Figure 3 is a top plan view of the forward end of the plunger, showing the compressor wings;

Figure 4 is a side elevational view of the construction shown in Figure 3;

Figure 5 is an enlarged side elevational view showing the cover in closed position;

Figure 6 is a top plan view of the parts shown in Figure 5;

Figure 7 is a cross section on line 7—7 of Figure 6.

Describing in detail the particular construction shown in the drawings, 1 designates the frame of a baler which is preferably formed with uprights 2 and 3, main side bars 4 and lower side bars 5, the uprights being connected by suitable cross bars 6. The side bars 4 preferably extend forwardly of the upright 2 and are inwardly inclined towards each other so as to form the tapering sides 7 and 8 of the compressor box, these sides being lined on the inner side and the bottom with renewable facings 9. As shown in Figure 1 the side bars 4 and the sides of the compressor box form a continuous side, preferably constructed of channel iron, and at the forward end of the compressor box the sides 7 and 8 are connected by bolts 10 extending through the end piece 11. The bottom of the compressor box is supported on a sub-frame 12 which rests on the cross bars 6 of the uprights 2, while at the top the compressor box is provided with a cover 13 pivoted at 14 and counterbalanced by suitable weights 15. When the cover 13 is moved down to its closed position at the top of the compressor box, it is locked in this position by a locking member 16.

As it is often necessary to force the cover down against the tension of some of the metal which projects up above the sides of the compressor box, I have arranged the novel locking and tightening mechanism

shown in Figures 1 and 2. This locking member 16 comprises a bar 17 which at its upper end has a casting 18 which can be adjusted longitudinally of the bar 17 by means 5 of the handle 19. The lower end of the rod 17 is provided with a loop 20 fitting over a cam 21 which is operated by the foot pedal 22. This cam is so arranged that by pressing down on the pedal 22 or the turn wheel 10 22' the cam is rotated to positively draw the cover section 13 down into close contact with the top of the compressor box. In use the cover 13 is first turned downward on to the compressor box and the casting 18 placed 15 over the end of the cover and the handle 19 turned to draw the cover down as tight as possible. The foot pedal 22 is then forced downward and through the action of the cam completes the tightening operation. It 20 will be noticed that a single locking mechanism is employed for holding the cover section in place and as the rear ends 23 of the cover rest beneath the top cross bars 24 when the cover is in its closed position, there 25 is no possibility of its being forced away from the top of the compressor box.

After the metal has been inserted and the compressor box cover fastened in place as above described, the plunger 25 is forced 30 forwardly by the toggle mechanism 26 in the manner hereinafter described. This plunger is pivotally connected to the toggle arm 27 so that when the latter moves forward the plunger will be forced forwardly 35 toward the narrow portion of the compressor box. To assist in compressing the material the plunger is provided with wings 28 and 29 which are secured to the sides of the plunger by elongated pivot members 30. 40 The detail of the plunger and its wings or side arms 28 and 29 is shown in Figures 3 and 4. In order to reduce the cost of manufacture the front end of the plunger is preferably formed as a plate 32 which is made 45 of hard steel, while the other part of the plunger can be formed of sheet metal. While the arms or wings 28 and 29 are secured to the plunger by the pivots 30, the arrangement of parts is such that the stress 50 is not transmitted through these pivots, but is passed directly from the arms 28 and 29 to the plunger.

As shown in Figures 3 and 4 the ends 33 and 34 of the arms 28 and 29 are grooved 55 to fit into recesses 35 and 36 in the front plate of the plunger, the ends 33 and 34 being cut away at the top and bottom portions to receive lugs 37 and 38 carried by the plunger. These lugs are apertured to permit of the passing of the pin or pivot 30 through the lugs and the wings 28 and 29. To give a wide bearing surface between the wings and the compression box the arms or wings 28 and 29 are tapered at 39 and 40 60 to correspond with the inclination of the

side walls of the compression box and preferably have an additional bevel at the tip portions 41 and 42. The forward movement of the plunger is guided by a bar or guide 43 which fits in a groove on the lower side 70 of the plunger.

In order to secure the necessary length of the compression box and give sufficient length to the arms, the latter are preferably made longer than the final length of the 75 bale and after the first compression the plunger is withdrawn and a reducing block 44 inserted, after which a second compression is given so as to further compress the bale. To avoid the necessity of lifting the 80 cover 13 after each of the compression strokes so as to admit the reducing block, I have provided a novel arrangement where- 85 in there is a door or covered opening 45 formed in the cover near the rear end thereof. When the plunger is drawn back for the second compression stroke this cover can be lifted and the reducing block inserted just forwardly of the plate 32 of the plunger, after which the compression opera- 90 tion is the same as the preceding one except that the material is further compressed into a smaller space.

Taking up now the toggle construction and the drive mechanism, it will be noticed 95 in Figure 1 that the toggle arm 27 is connected to the back toggle link 47, which toggle link at its lower end is pivoted at 48, the pivot point being located in the plane of the side frames 4 so that the fulcrum point 100 for the plunger is in direct line with the compression box. In this manner it is possible to secure the necessary strength of the frame without using heavy castings, although to accurately line up the sides of the 105 frame there is preferably employed a cross member 49 which has at its sides machined faces which receive the inner faces of the main side bars 4 of the frame. The connecting rod 52 of the toggle is pivotally connected to a rod 53 which is carried by the 110 large gears 54 mounted on stub shafts 55 and supported in the side piece 56.

To secure the necessary compression the 115 following drive mechanism is employed between the connecting rod 52 and the motor 57 or other suitable source of power. In this connection it will be noticed that the rear end of the frame is so constructed as to form a platform on which the motor stand- 120 ard 58 can be mounted, thus making a complete and self-contained portable structure.

The fly wheel 59 is mounted in a casing 59'. The original drive shaft 60 carries a small pinion 61 meshing with a larger gear 62 located inside of the side frame bars 4. The gear 62 is secured to a shaft 63 which projects outside of the frame and has an outside pinion 64 which meshes with the gear 65 formed in the fly wheel 59. The 125 130

latter is mounted on the shaft 66 which in turn has a pinion 67 located inside of the frame and adapted to drive the bull wheels or gears 54. The rotation of these gears 5 draws the connecting rod 52 forwardly and rearwardly and through the action of the toggle arm 27 forces the plunger 25 forwardly, compressing the metal in the compressor box, as previously described. In 10 doing so the entire force is transmitted in a straight line through the sides 4 of the frame.

After the bale has been formed in the compressor box the locking member 16 is 15 released and the cover 13 rocked back to its open position. In order to facilitate the removal of the bale from the compressor box means are provided for loosening it at the extreme forward end, which is the main part 20 that would tend to bind. For this purpose a bale kicker 68 is employed. This kicker comprises an offset rod or rocker arm which is pivoted at 69 and has a projection 70 adapted to be forced up into the plane of 25 the bale whenever the foot pedal 71 is forced downward. It will of course be understood that a handle could be substituted for the foot pedal 71. After the bale has been initially released by operating the kicker, the 30 latter will be returned to its inoperative position automatically by the spring 72.

I do not, however, desire to limit the invention to the particular form of this locking and releasing mechanism or to the particular arrangement of the various parts except as ultimately set forth in the claims.

What I claim as my invention is:—

1. In a baler, the combination with a compression box and a plunger operating in said compression box, of a frame for supporting said parts having an upright, a cover member pivotally carried by said frame, and a cross bar carried by said frame beneath which one end of the cover is held when the cover is in use, and a single locking member for holding the other end of said cover.

2. In a baler, the combination with a compression box, of a plunger operable therein, said compression box having its sides and bottom provided with renewable linings of harder metal than the compression box.

3. In a baler, the combination with a compression box, of a plunger operable therein, said compression box having its sides and bottom provided with renewable linings of harder metal than the compression box, said plunger also having a renewable facing.

4. In a baler, the combination with a compression box having tapering sides and a plunger operating therein, said plunger hav-

ing a pair of pivoted wings which are adapted to be contracted towards each other by the engagement with the sides of the compression box when the plunger is moved forward, the outer surfaces of said wings 65 having a relatively wide bearing portion tapered to correspond with the taper of the sides of the compression box.

5. In a baler, the combination with a compression box, of a plunger mounted to be reciprocated in said box, said box having its bottom provided with a longitudinally extending guide and said plunger having a co-operating slot engaging said guide during the reciprocating movement of said plunger. 70 75

6. In a baler, the combination with a plunger and operating means therefor, of a frame supporting said operating means, a compressor box at one end of said frame, a cover hinged upon said box, a cross bar of 80 said frame extending over the hinged end of said cover, and means for retaining said cover in closed position, said means including a long movable member, an adjustable member carried by said member and engageable with said cover for clamping the same against said compressor box, and means for moving the first-mentioned member longitudinally to increase the clamping pressure of 85 the last-mentioned member against said 90 cover.

7. In a baler, the combination with a compressor box and a cover therefor, of means for retaining the cover in closed position, said means including a rod having a loop at 95 the lower end thereof, a cam in the loop, a member adjustable longitudinally of the rod and engageable with the cover for clamping the cover against the compressor box, and means for actuating the cam after the member aforesaid has been adjusted for increasing the clamping pressure exerted against 100 said cover.

8. In a baler, the combination with a plunger and operating means therefor, of a frame supporting the operating means and including forward and rear uprights, upper side bars connected to said forward and rear uprights, lower side bars connecting said forward and rear uprights, the upper side 110 bars being formed of structural metal and projecting beyond the front uprights, the projecting portions of the upper side bars inclining toward each other and forming the sides of a compressor box for receiving the plunger aforesaid, and a member connecting the projecting portions of the upper side bars at the forward ends thereof. 115

In testimony whereof I affix my signature.

GEORGE W. LANGFORD.
